REFRIGERATING APPARATUS

Charles F. Kettering, Dayton, Ohio, assignor to
General Motors Corporation, Dayton, Ohio, a
corporation of Delaware

Application March 28, 1936, Serial No. 71,498

8 Claims. (Cl. 62—4)

This invention relates to refrigerating apparatus and more particularly to refrigerant air conditioning means and control means therefor.

This application is a continuation in part of application Serial No. 583,878, filed December 30, 1931.

Heretofore, air conditioning means have been largely controlled by the temperature of the air. However, in many ways and for many purposes such a control has been found deficient. For example, for many industrial processes it is required that not only the temperature but also the humidity be kept constant. For air conditioning for comfort purposes it is desirable that the temperature vary to a certain extent according to variations in outside temperature and it is further desirable to provide a lower relative humidity at high temperatures and a higher relative humidity at low temperatures.

It is an object of my invention to provide means for starting and stopping a refrigerant air conditioning system according to predetermined limits of humidity, either with or without a correlated temperature control.

Heretofore humidity control means have been very delicate, and expensive and yet not always sufficiently sensitive. It is another object of my invention to provide a humidity control means for a refrigerant air conditioning system which is reliable, durable and inexpensive.

It is another object of my invention to provide an extremely sensitive controlling device wherein little power is required to initiate and govern its operation and in which relatively heavy electric current can be controlled by the use of a simple reliable and novel relay apparatus.

Another object of my invention is to provide an improved electrical humidity control mechanism for refrigerant air conditioning apparatus employing a Wheatstone bridge circuit and wet and dry bulb resistance thermometers in the arms of the bridge circuit.

Further objects and advantages of the present invention will be apparent from the following description, reference being had to the accompanying drawings, wherein a preferred form of the present invention is clearly shown.

In the drawings:

Fig. 1 is a view partly in section of a refrigerant air conditioning apparatus embodying one form of my invention;

Fig. 2 is a front view of a portion of the control apparatus with the cover removed;

Fig. 3 is a side view of the apparatus shown in Fig. 2 with part of the casing broken away;

Fig. 4 is a diagrammatic view of an air conditioning apparatus of the compression type together with another form of improved humidity control apparatus;

Fig. 5 is a plan view of a form of my improved portable refrigerant dehumidifying air conditioning apparatus including the humidity control apparatus of Fig. 4; and

Fig. 6 is an elevational view of the apparatus shown in Fig. 5.

Briefly, in Figs. 1 to 3 inclusive, there is shown a refrigerant air conditioning system of the compression type in which the liquefying apparatus is located outside of the room and the evaporating means as well as the humidity control means is located within the room. The humidity control means includes a humidity responsive paper strip for actuating a switch means which in turn operates a motor relay which in turn controls the starting and stopping of the motor-compressor unit according to humidity conditions within the room. In Fig. 4 a somewhat similar air conditioning system is shown wherein the control employs a Wheatstone bridge circuit having a wet and a dry bulb thermometer in two arms thereof, an adjustable resistance in the other two arms and a relay in the center which in turn controls a relay operated switch in series with the compressor motor so as to start and stop the operation of the motor-compressor unit according to predetermined high and low humidity conditions. In Figs. 5 and 6 the control, shown in detail in Fig. 4, is shown applied to a portable dehumidifying unit which includes a motor-compressor unit, condenser and evaporator which is placed within the room merely to remove the moisture therefrom without cooling the room.

Referring to the drawings and more particularly to Fig. 1, there is disclosed a refrigerant dehumidifying apparatus comprising a cabinet 20 located within a room 21 to be cooled and dehumidified. Within the cabinet there is provided a refrigerant evaporating means 22 over the surfaces of which the air in the room is circulated by means of a centrifugal fan 23 located in the lower portion of the cabinet 20. The centrifugal fan 23 draws air from the interior of the room and circulates the air over the surfaces of the evaporator 22 after which the air is discharged through a grilles opening 24 in the top of the cabinet 20. The refrigerant evaporating means 22 is supplied with liquid refrigerant by the refrigerant liquefying apparatus which draws refrigerant vapor from the evaporating means through the suction conduit 26, compresses the

vapor and forwards the compressor vapor to a condenser 27 where the vapor is liquefied and collected in a receiver 28. From the receiver 28 the liquid refrigerant is forwarded through a supply conduit 29 under the control of a suitable expansion valve 30 to the evaporating means 22.

The compressor 25 is driven by an electric motor 35 which is supplied with electric energy through the electric conductors 36 and 37. In order to control the operation of the dehumidifying apparatus, and, in particular, the operation of the electric motor 35, I provide a control member 38, preferably of the sealed mercury type, which when tilted in one direction closes the circuit to the electric motor and which when tilted in the opposite direction opens the electric circuit. The tilting of the mercury tube control member 38 is controlled by a small high resistance electric clock winding motor 39 whose operation is controlled by a humidity responsive means 40. This humidity responsive means 40 is necessarily located in the room 21, the humidity of which it is desired to control and is preferably located at some point which will indicate the average humidity condition of the room.

This humidity responsive means comprises a base upon which a long paper strip 41 is coiled. This paper strip is connected to a pin 42 mounted in the base at one end and to a lever 43 at its opposite end. This lever 43 preferably extends downwardly from its pivot so that the paper strip when it changes its length in accordance with changes in humidity is not required to overcome the force of gravity in order to operate the lever. The lever is provided at its lower end with a switch contact 44 which cooperates with a stationary contact 45 mounted upon the base. Contacts 44 and 45 are connected in series with the electric motor 39 in the electric circuit 46 which is connected in parallel with the electric motor 35.

Referring now more particularly to Figs. 2 and 3 for the details of the control member 38, and its actuating means, there is shown a generally rectangular base 50 provided with a removable cover 51 having a plurality of windows 52 in its lower portion for disclosing the position of the mercury tube contact member 38. Mounted upon the base 50 beneath the cover 51 is the small high resistance electric clock winding motor 39. The resistance of the clock is sufficient to prevent injury to the winding even when the motor is stalled for long periods of time. The electric clock winding motor 39 is supplied with electric energy through the electric conductors 53 and 54 which form a part of the electric circuit 46. The electric motor 39 is mounted upon pedestals 54 which support the motor but hold it spaced from the base. The motor shaft 55 extends from the motor toward the base and has its end extending into a bearing within the base 50.

The portion of the motor shaft 55 between the motor proper and the base is provided with a pinion 56 which meshes with a gear 57 carrying a pinion 58 which in turn meshes with a sector gear or rack 59 which is mounted upon a shaft 60 which is mounted at one end in the base 50 and at the opposite end in the frame member 61. Supported upon the sector gear 59 is a clip 62 having four prongs which engage the mercury tube contact member 38. The mercury tube contains a globule of mercury 63 and a pair of contacts 64 which are in series with the electrical conductor 36. The base is provided with

stop pins 65 and 66 which engage the sector gear and limits its rotation in either direction.

When the contacts 44 and 45 are in open position and no electric energy is supplied to the high resistance electric motor 39, the spring 67 urges the sector gear 59 in a counterclockwise direction and holds it against the stop pin 65. When the contacts 44 and 45 close, the clock winding motor 39 is energized to cause the sector gear to be moved in a clockwise direction to a position against the stop 66 against the tension of the spring 67. This completes the circuit through the electric motor 35 and causes the refrigerant liquefying apparatus to operate. The electric motor 39 remains energized so long as the contacts 44 and 45 remain closed and continues to hold the sector gear 59 against its stop pin 66 to hold the mercury tube control member in its extreme clockwise position so that the globule of mercury 63 will bridge the gap between the set of contacts 64, thus completing the electric circuit.

When the room 21 has been sufficiently dehumidified, the contacts 44 and 45 will separate, causing the clock winding motor 39 to de-energize. This will permit the spring 67 to return the sector gear 59 to its initial position against the stop pin 65. In returning the sector gear to its initial position, the train of gears and the motor is rotated. It is therefore necessary that the clock winding motor and the train of gears have as little friction as possible so that they operate freely in both directions.

In Fig. 4 I have shown for the purpose of illustrating my invention an air conditioning apparatus of the compression type including a compressor 120 for compressing the refrigerant and for forwarding the compressed refrigerant to a condenser 121 where the refrigerant is condensed and collected in the receiver 122. From the receiver 122 the refrigerant is forwarded through supply conduit 123 to an expansion valve 124 which controls the flow of refrigerant into the evaporator 125. The refrigerant evaporates under reduced pressure in the evaporator 125 and is returned to the compressor through the return conduit 126. The compressor 120 is driven by a suitable electric motor 127 through pulley and belt means 128. The evaporator 125 is preferably positioned within the room to be conditioned or in communication with the room or place to be conditioned.

The refrigerant liquefying apparatus, comprising a compressor, a motor for driving the compressor, and a condenser may be placed in the room to be conditioned or it may be placed outside of the room to be conditioned and connected to the evaporator through the supply and return conduits 123 and 126. For the purpose of increasing the amount of air passing over the heat transfer surfaces of the evaporator 125 a fan 130 driven by an electric motor 131 provided within a duct 132 is employed for blowing a stream of air over the evaporator 125. The evaporator 125 cools the air, and if desired will dehumidify the air by cooling the air below its dew point, causing moisture to collect upon the evaporator 125 and to run down the surfaces of the evaporator 125 and collect in the catch pan 133, from which the condensed moisture will pass through a conduit 134 to a cup 135, which is kept supplied with water thereby, and from which point the excess is conducted to drain through the conduit 136.

An improved electrical control apparatus is

provided for controlling the operation of this air conditioning apparatus. This control apparatus is applicable to any form of apparatus which changes the amount of humidity in air or any other gas. In this electrical control apparatus there is provided a Wheatstone bridge circuit generally designated by the reference character 140 having a dry electrical resistance thermometer 141, preferably non-inductively wound, in one of the arms of the bridge circuit, a wet resistance thermometer 142 in another arm of the bridge circuit, and adjustable resistances 143 and 144 in the other arms of the bridge circuit. The wet resistance thermometer 142 as well as the adjustable resistances 143 and 144 are also preferably non-inductively wound so that alternating current, if desired, may be used for energizing the Wheatstone bridge circuit. The bridge circuit is supplied with electric current by the electric conductors 148 and 149 which are connected to both ends of the bridge circuit, the conductor 148 being connected between the wet and dry resistance thermometers 142 and 141 while the conductor 149 is connected between the adjustable resistances 143 and 144. These electric conductors 148 and 149 may be supplied with direct current or with alternating current of a suitable voltage. If desired, alternating current supplied from a transformer connected to the main circuit or any suitable source of alternating current may be used for supplying the current necessary for the use of the Wheatstone bridge circuit.

The wet resistance thermometer 142 is provided with a stockinet 145 covering its surface and a wick 146 which dips into the water within the cup 136 and supplies moisture to the stockinet 145. Both the wet resistance thermometer 142 and the dry resistance thermometer 141 are placed within the duct means 132 so that the air which is drawn through the duct by the fan 130 is drawn over the surfaces of these two thermometers before it is blown over the surfaces of the evaporator 125. The dry resistance thermometer 141 will therefore be responsive to the dry bulb thermometer temperature of the air in the place to be conditioned and the wet resistance thermometer 142, by reason of the evaporation of moisture in the stockinet caused by the air passing thereover, will be responsive to the wet bulb temperature of the air in the room or place conditioned. A normally closed relay 147 is connected to the sides of the Wheatstone bridge circuit between the dry resistance thermometer 141 and the adjustable resistance 143 on one side and between the wet resistance thermometer 142 and the adjustable resistance 144 on the other side.

It is often desirable to operate the apparatus so as to maintain the proper relative humidity at different temperatures. This desired relative humidity will depend upon the particular purpose for which the air is to be conditioned. For drying purposes the main object is to obtain as low a humidity as possible if rapid drying is desired. In textile mills the humidity must be carefully controlled for proper spinning, weaving and winding. For comfort it is desirable that the relative humidity should be lower at higher temperatures. My improved control mechanism can provide a control having any character desired.

If it is desired that the relay should close and the apparatus begin to operate when the relative humidity reaches approximately 100%, the wet

and dry resistance thermometers may be made of substantially the same kind of wire and the resistances 143 and 144 are adjusted to be substantially equal. With the bridge circuit arranged in such a manner when the humidity reaches approximately 100%, the temperature of the dry resistance thermometer 141 and the wet resistance thermometer 142 will be substantially the same since very little evaporation will take place from the stockinet. Under these conditions the current flowing through the relay 147 will be at a minimum and the relay contacts will be permitted to move to closed circuit position.

If it is desired to maintain a certain wet bulb depression of temperature throughout the range of temperatures the resistances 143 and 144 may be adjusted to make the current flowing through the relay 147 at a minimum permitting the relay to close when the minimum wet bulb depression has been reached. Under these conditions the resistance 144 will be adjusted to have a lower value than the resistance 143. From the table compiled below it will be seen that a constant wet bulb depression does not give a constant relative humidity.

Percent relative humidity

D. B. temperature °F.	5° F. de- pression Percent	10° F. de- pression Percent	15° F. de- pression Percent	30
65.....	75	53	33	
70.....	78	56	37	
75.....	79	59	41	
80.....	80	62	44	
85.....	81	64	47	
90.....	83	66	50	35
95.....	83	67	53	

If it is desired to have a constant relative humidity the dry resistance thermometer 141 and the wet resistance thermometer 142 are made of different materials so that the electrical resistance of the resistance thermometer 142 increases more rapidly with increase in temperature than with electrical resistance of the dry resistance thermometer 141. For example, such an effect can be obtained by using copper wire in the wet resistance thermometer 142 and German silver wire in the dry resistance thermometer 141, since the resistance of copper per ohm per degree centigrade at 20° centigrade increases .0041 ohm while under the same conditions the resistance of German silver increases only .00036 ohm. This method can also be employed to obtain a lower relative humidity at higher temperature and a higher relative humidity at lower temperatures by properly selecting the materials used in the thermometers. This condition of relative humidity is much more desirable for personal comfort. If desired, however, instead of using such a means to compensate for variations in temperature, the relay 147 may be adjusted or provided with a temperature compensating bulb for varying the operation of the relay according to the temperature.

The relay 147 is employed to open and close the relay circuit comprising the conductor 151, the secondary winding 152 of the transformer 153, the relay coil 154 and the electric conductor 155. The relay, generally designated by the reference character 165, as well as the transformer 153 are all situated within an enclosed switch housing 156. The opening and closing of the relay circuit by the relay 147 causes the relay 165 to open and close the main supply circuit of the apparatus comprising the electrical con-

ductors 157 and 158. The fan motor 131 and the compressor motor 127 are supplied with electric current through the electric conductors 157 and 158 from the power lines. The electric conductor 158 is connected to the relay switch 159, operated by the relay coil 154 and the relay 165, which switch connects at suitable times the electric conductor 158 with the electric motor 127 through the electric conductor 160 as well as 10 the electric fan motor 131 through the electric conductor 161. The electric conductor 162 completes the electric circuit of the fan motor 131. The transformer 153 is provided with a primary winding 163 which is supplied with current from 15 the electric conductor 158. When the relay 147 is closed, the relay 165 closes causing the electric motors 127 and 131 to drive a compressor 120 and fan 130 respectively thus causing the air conditioning apparatus to operate. When the 20 relay 147 opens, the relay 165 will open and stop the operation of the apparatus. In this way the air conditioning apparatus will be intermittently operated to maintain the desired humidity.

In damp places and in drying rooms it is usually desired to dehumidify the air without any reference to the temperature of the air. Indeed, in many cases it is desirable that the temperature of the air be increased. For this purpose I have provided a unitary portable air conditioning apparatus controlled by my improved electrical humidity control apparatus for effectively dehumidifying the air within the place desired. Referring to Figs. 5 and 6 I have shown a portable dehumidifying apparatus mounted on a 25 platform 170 including an air-cooled compressor 171 mounted thereon for compressing the refrigerant and for forwarding the compressed refrigerant through the conduit 172 to an air-cooled fin-type condenser 173 where the refrigerant is condensed and forwarded through the conduit 174 to a receiver 175 where this liquefied refrigerant is collected. From the receiver 175 the liquid refrigerant is forwarded through the supply conduit 176 to an expansion valve 177 which controls the flow of liquid refrigerant to 30 the finned evaporator 178 which is situated directly aside of the condenser 173. The condenser and evaporator 173 and 178 are provided with a hood over the top portion. The refrigerant in the evaporator evaporates under reduced pressure and is returned to the compressor through the return conduit 179. All of the above mentioned apparatus is mounted on the platform 170. An electric motor 180, also supported on the 35 platform, is provided for driving the compressor through pulley and belt means 181.

The motor 180 and the compressor 171 are both provided with means for drawing air first through the evaporator and then through the condenser 60 173 and then over the motor 180 and the compressor 171. For this purpose the motor pulley adjacent the condenser 173 is provided with fan 183 and the combined pulley and flywheel of the compressor 171 is provided with fan blades 184 for drawing air first through the evaporator 178, then through the condenser 173 and finally directing the air over the motor 180 and the compressor 171. In this way the air is first cooled 65 below its dew point in the evaporator which removes moisture from the air, and then the air passes directly into the condenser 173 which transmits the excess heat of the compressed refrigerant to the air thus condensing the refrigerant and warming the air, and finally the air is discharged over the motor and compressor which

also give up heat to the air further warming the air. By warming the air with the condenser, compressor and motor the relative humidity is greatly reduced. The system operates highly efficiently since the condenser 173 is cooled by 5 the relative cold air coming from the evaporator 178.

The apparatus is preferably controlled by the improved electrical control apparatus shown in Fig. 4 and has the Wheatstone bridge circuit including the wet and dry resistance thermometers and the relay provided within an enclosure 186 having louvers therein for allowing the air to pass over the wet and dry resistance thermometers on its way to the evaporator 178. This enclosure 15 containing the bridge circuit is preferably placed in the path of the air moving to the evaporator 178. It, however, may be placed in any portion of the room desired, but preferably it should be placed where it will be responsive to the true 20 relative humidity of the room. The primary relay as well as the transformer for the secondary relay circuit are enclosed in the box 187. The electric current for the motor 180 is supplied through the electric conductors 188 and 189. The 25 electric current is supplied to the Wheatstone bridge control circuit through the conductors 190 and 191. The electric conductors 192 and 193 connect the primary relay housed within the box 187 and the secondary relay which is housed 30 within the enclosure 186. The electric conductors 194 and 195 conduct electric current from the box 187 to the electric motor 180.

With this type of dehumidifying apparatus the maximum drying effect is obtained, as well as the 35 maximum efficiency. This is accomplished by reason of the fact that the air cooled by the evaporator is employed for cooling the condenser, the compressor and the electric motor which raise the temperature of the air without increasing its 40 humidity content. The moisture condensed by the evaporator 178 is collected in a catch pan 196 from which it is removed by means of a drain pipe or other convenient means. My improved control apparatus so controls its operation of the 45 electric motor 180 so as to prevent the humidity from rising above the permissible maximum.

I claim:

1. An air conditioning apparatus for conditioning air including a refrigerant evaporating means 50 in heat exchange relation with the air to be conditioned, a refrigerant liquefying means for supplying liquid refrigerant to and for withdrawing evaporated refrigerant from the evaporating means, and humidity responsive control means 55 for starting and stopping the operation of the liquefying means according to humidity conditions of the air to be conditioned.

2. An air conditioning apparatus for conditioning air including a refrigerant evaporating means 60 and means for circulating the air to be conditioned into heat exchange relation with said evaporating means, a refrigerant liquefying means for supplying liquid refrigerant to and for withdrawing evaporated refrigerant from the 65 evaporating means, and humidity responsive control means for starting and stopping the operation of the liquefying means according to humidity conditions of the air to be conditioned.

3. An air conditioning apparatus for conditioning air including a refrigerant evaporating means 70 in direct heat exchange relation with the air to be conditioned, a refrigerant liquefying means for supplying liquid refrigerant to and for withdrawing 75 evaporated refrigerant from the evaporating

means, control means for controlling the starting and stopping of the refrigerant liquefying means, said control means including a humidity responsive means.

5. An air conditioning apparatus including an enclosure to be conditioned, a refrigerant evaporating means, means for circulating the air in said enclosure into heat exchange relation with the evaporating means, a refrigerant compressing and condensing means operably connected to the evaporating means for supplying liquid refrigerant to and for withdrawing evaporated refrigerant from the evaporating means, said compressing and condensing means being isolated from the air within the enclosure, and humidity responsive means responsive to predetermined high humidity conditions to start the compressing means and responsive to predetermined low humidity conditions to stop the compressing means.
10. An air conditioning system for conditioning air comprising a refrigerant evaporating means in direct thermal exchange relation with the air to be conditioned, a refrigerant liquefying and circulating means for withdrawing vaporized refrigerant from and for supplying liquefied refrigerant to said evaporating means, and humidity responsive means for controlling the circulation of the refrigerant.
15. An air conditioning system for conditioning air comprising a refrigerant evaporating means in

direct thermal exchange relation with the air to be conditioned, a refrigerant liquefying and circulating means for withdrawing vaporized refrigerant from and for supplying liquefied refrigerant to said evaporating means, and humidity responsive means for starting and stopping the circulation of the refrigerant by said liquefying and circulating means.

7. An air conditioning apparatus for conditioning air for an enclosure including a refrigerant evaporating means, a refrigerant liquefying means for supplying liquid refrigerant to and for withdrawing evaporated refrigerant from the evaporating means, and humidity responsive control means for controlling the operation of the liquefying means in accordance with humidity conditions of air in said enclosure.

8. The combination with a building having a room and an air conditioning apparatus therein, said air conditioning apparatus embracing a refrigerating system and a fan for circulating air therethrough, means for electrically operating said refrigerating system and said fan, a relay switch for controlling said means, a transformer for operating said relay switch and a device responsive to a psychrometric function of air arranged in said building for controlling the flow of current through said transformer.

6. An air conditioning system for conditioning air comprising a refrigerant evaporating means in

CHARLES F. KEITTERING. 30
